END FRAME FOR A DYNAMOELECTRIC MACHINE

Doran D. Hershberger, Sycamore, Ill., assignor to
General Electric Company, Fort Wayne, Ind.

Filed Apr. 21, 1972, Ser. No. 246,514

Term of patent 14 years

Int. Cl. D13—01

U.S. Cl. D26—5 A

FIG.1

FIG.2

FIG. 1 is an end elevational view of an end frame for a dynamoelectric machine showing my new design; and

FIG. 2 is a perspective view thereof it being understood that the broken lines are for illustrative purposes only.

I claim:

The ornamental design for an end frame for a dynamoelectric machine, as substantially shown and described.
